DIODE RECTIFIER

Earl P. Lind, Belleville, Ontario, Canada, assignor to
Northern Electric Company, Limited, Montreal, Can-
ada, a corporation of Canada

Filed Jan. 23, 1963, Ser. No. 73,286

Term of patent 14 years

(Cl. D26—15)

FIG. 1 is a front elevational view of a diode rectifier, showing my new design, the rear and sides having substantially the same appearance;

FIG. 2 is a top plan view; and

FIG. 3 is a bottom plan view thereof.

I claim:

The ornamental design for a diode rectifier as shown and described.
